CLAIM

The ornamental design for a fuel dispenser interface, as shown and described.

DESCRIPTION

FIG. 1 is a top, front, and left side perspective view of a fuel dispenser interface showing our new design;

FIG. 2 is a rear elevational view; and,

FIG. 3 is a side elevational view.

The bottom and top views of the design are not shown and would not depict any aspect of the invention not already shown in the figures.

The bottom, top and rear elevation views of the design are not shown and would not depict any aspect of the invention not already shown in the figures.

Our new design comprises, essentially, an interface for fuel dispensers. The broken-line disclosure of a fuel dispenser and portions thereof in the views is for environmental purposes only and forms no part of the claimed design.
